UNITED STATES PATENT OFFICE.

CHARLES BLAUL, OF MORTON GROVE STATION, AND FELIX H. KIMMICH, OF CHICAGO,
ILLINOIS.

COMBINATION CONVEYER AND DRIER FOR BRICKS.

1,129,444.

Specification of Letters Patent. Patented Feb. 23, 1915.

Application filed May 8, 1914. Serial No. 837,124.

To all whom it may concern:

Be it known that we, CHARLES BLAUL, residing at Morton Grove Station, in the county of Cook and State of Illinois, and 5 FELIX H. KIMMICH, residing at Chicago, in the same county and State, both citizens of the United States, have invented a certain new and useful Improvement in Combination Conveyers and Driers for Bricks, of 10 which the following is a specification.

Our invention relates to conveyers, more particularly combination conveyers and driers for use in the manufacture of bricks.

The object of the invention is to provide 15 apparatus in which the pallets upon which the bricks are supported may be readily detachable; second, to provide means whereby the green bricks may be dried preparatory to burning; third, to accomplish certain ad- 20 vantageous details of construction which will be hereinafter more particularly described and claimed.

We accomplish our objects by the apparatus in which—

25 Figures 1, 2 and 3 are side, plan and end views respectively of apparatus embodying our invention. Fig. 4 is a plan view of a portion of the conveyer chain and associated parts together with a fragment of one of the 30 pallets. Fig. 5 is a plan view of the parts shown in Fig. 4, this view being partly in section on the line 5—5, Fig. 4. Fig. 6 is a vertical sectional view on the line 6—6, Fig. 4. Fig. 7 is a perspective view of a pallet 35 support.

Similar numerals refer to similar parts throughout the several views.

It will be understood by those familiar 40 with the manufacture of brick, especially “common” brick, that as the bricks, in their green condition, leave the machine they are usually placed by hand upon a conveyer belt for the purpose of removing them from the machine and advancing them in their 45 progress toward the kiln. To facilitate an understanding of our machine, more particularly with reference to its use in brick making, let it be assumed that the dotted lines A at the left end of Fig. 2 indicate 50 the adjacent edge of a belt or other conveyer which receives the bricks from the machine. Ordinarily this belt will run parallel to the kilns so that the bricks may be brought adjacent to the desired part thereof. Let it be 55 assumed that our machine (of which there

will ordinarily be a number) is located transverse to belt A, and with its receiving or head end so near belt A that two operators, standing on opposite sides of our machine, may, without leaving their position, 60 remove the bricks from the belt and place them upon the pallets of our machine. The movement of the pallets will be away from belt A.

Referring now more particularly to the 65 construction of the machine itself, two endless metallic belts are formed of the links 1, 1 which are articulately connected together in parallel by pins 2. These pins constitute the axles for anti-friction rollers 70 3, 3 which roll upon two parallel tracks 4. In the preferred construction, these tracks have a special configuration best seen in cross-section in Fig. 6. In this form the track is made of formed sheet metal having 75 a central raised portion 4^a upon which the rollers run. Connected with this central raised portion are two trough-like portions 4^b, 4^b which come up on the side high enough to serve as a guard for the link belt and 80 parts thereon. The link belts pass over end sprockets 5 and 6, the sprockets 5 being at the head or receiving end of the machine and the sprockets 6 at the delivery end. The sprockets 5 are mounted upon a shaft 85 7 journaled in standards 8. The sprockets 6 are mounted upon short shafts or trunnions 9, 9 journaled in adjustable boxes 10, mounted on the standards 11. The object in thus leaving the central part of the machine clear 90 at the delivery end is to permit the entry of a car in case cars are employed in carrying away the bricks from our machine. Fastened to the belts at suitable intervals are 95 pallet carriers, the best form whereof is 95 shown in perspective in Fig. 7. According to the design here shown, each carrier is provided with two lugs 13 which are transversely apertured to receive studs 14 by which said carriers are secured to the links 100 of the belt. It is desirable to provide flanges 15, 15 on said lugs for engaging the upper and lower edges of the links for insuring that the carriers shall stand upright. Said carriers have preferably four branches, 105 the branches 16, 16 extending lengthwise of the belt and the branches 17, 18 extending transversely thereto. The branch 18 lies toward the outer edge of the machine and is provided with wedge shaped lugs 19 to 110

facilitate the seating of the pallets. At the center of the carrier where the branches meet, there is a socket 20, provided with internal flanges 21, 21, for engaging and 5 releasably retaining the spring fingers 22 which are fastened to the under side of the pallets 23. We prefer to form the pallets of pressed metal in the manner best shown in Figs. 4, 5 and 6, in which the pallet is provided with drooping flanges 24, 24 along its longitudinal margins and a central rib 25 whereto the fingers 22 may be fastened. As a result of this construction, particularly of the spring fingers and the internally lipped 15 or flanged sockets 20, the pallets will normally be held securely seated upon the pallet carriers, but may be withdrawn by merely exerting a rectilinear pull of reasonable force. Ordinarily the fingers 22 will be 20 made strong enough to hold the pallets fast to the carriers even when depending therefrom as they will do when they are returning along the under side of the belt.

In the space formed between the upper 25 and lower edges of the link belts are steam coils 27 for heating the bricks above. The heat is confined to the machine and directed to the bricks by a set of baffle plates 28 located at suitable intervals apart. The heat 30 is retained at the side by side walls 29 as shown in Figs. 1 and 2. By preference the coils do not reach completely to the delivery end of the machine, it being desirable to afford a space there for admitting a car.

35 In operation, two operators will normally stand at the receiving end of the machine and will pile the bricks upon the nearest pallet or pallets. When these have been piled to the desired height, the operator will 40 cause the link belts and the pallets thereon to move one step—which ordinarily will be equal to the distance between the centers of two adjacent pallets, or possibly twice or thrice such distance. These fresh pallets 45 will be filled in a similar manner and then caused to move on as before. The movement of the belts and pallets will thus ordinarily be intermittent and they will be driven by any suitable mechanism which need not be 50 here shown. It is obvious, however, that a slow continuous motion of the belts and pallets would be possible. After the machine is completely filled, the operators leave it and go to the next machine, the first machine being permitted to stand a number of 55 hours to permit the bricks to dry. Ordinarily it is sufficient if the bricks are permitted to remain a period of 24 hours. When the bricks are sufficiently dry, they are removed 60 from the machine; and this may be accomplished in either one of several ways. They may be lifted off of the machine a brick at a time, or they may be removed by a brick handling machine. But according to the 65 method to which our machine is especially

adapted, a car will be run under the delivery end of the machine and when in position will be raised up bodily high enough to detach the pallets from the link belts. Then when the car is removed it will take a number of 70 pallets, together with the superposed bricks thereon, whence the car and its load may be run to the kiln or elsewhere. When operated in this manner, of course, the pallets will not follow around to the under reach 75 of the belt, as shown in Fig. 1, but will occupy only the upper reach or top of the machine.

It will be noted that in our construction the pallets may be placed or removed by 80 moving them in a straight line directly toward or from the pallet carriers. No side movement or turning is required and no fastening devices need be manipulated. The fingers 22 catch automatically and have sufficient rigidity to hold the pallets in place until conscious pressure is exerted upon them for removal. The pallets are sure to seat properly both because of the fact that the fingers converge at their lower end and 90 also because of the converging sides of the lugs 19. It will be noted also, that as the pallets when loaded engage the pallet carriers at four points on opposite sides of the center, the pallets themselves assist in holding the carriers upright and eliminate any tendency of the carriers to rock transversely 95 to the path of travel.

Having thus described our invention, what we claim as new and desire to secure 100 by Letters Patent, is:

1. In a machine of the class described, the combination of a belt, pallets, and connections whereby a pallet may be detachably attached to the belt, said connections comprising two interfitting parts one of which is releasably held in the other.

2. In a machine of the class described, the combination of two approximately horizontal endless belts, pallets, and connections for detachably attaching the pallets to said belts, said connections each consisting of two interfitting parts the movement whereof toward and from each other is confined practically to a straight line normal to the surface of the belt.

3. A combination conveyer and drier for bricks comprising two endless belts, a set of pallet carriers secured to said belts, and spring fingers on said pallets adapted to automatically engage said pallet carriers for detachably holding the pallets in engagement therewith.

4. A combination conveyer and drier for bricks comprising two parallel endless link belts, a plurality of pallet carriers secured at intervals to each of said belts, said carriers each having a central internally flanged socket, and pallets adapted to seat upon pallet carriers on different pallets, said pallets

having spring fingers adapted to enter said sockets and removably engage the flanges thereof.

5. A combination conveyer and drier for bricks, comprising two parallel endless link belts, pallet carriers fastened to each of said belts, each pallet carrier having a central socket, a pallet adapted to rest upon said pallet carriers on the two different belts, 10 each pallet having two projections on the under side, one for entering each of the sockets aforesaid, and branches on said pallet carriers extending longitudinally of the pallet and transversely to the belts for assisting to hold said carriers against rocking movement transverse to the line of travel.

6. A combination conveyer and drier for bricks, comprising two parallel endless belts, cross pallets detachably connected to said belts, steam coils located beneath the upper reaches of said belts and baffle plates arranged vertically at suitable intervals beneath the upper reach of the belt for upwardly directing the heat of said coils.

In witness whereof we have hereunto subscribed our names in the presence of two witnesses.

CHARLES BLAUL.
FELIX H. KIMMICH.
